UNITED STATES PATENT OFFICE.

ALBERT AMOS ASTON, OF LEICESTER, ENGLAND, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR INSERTING FASTENINGS.

1,346,157.

Specification of Letters Patent.

Patented July 13, 1920.

Application filed August 15, 1916. Serial No. 115,001.

To all whom it may concern:

Be it known that I, ALBERT A. ASTON, a subject of the King of England, residing at Leicester, Leicestershire, England, have 5 invented certain Improvements in Machines for Inserting Fastenings, of which the following description, in connection with the accompanying drawings, is a specification, like reference characters on the drawings 10 indicating like parts in the several figures.

This invention relates to machines for inserting fastenings, and the general object of the invention is to provide an improved machine of this class especially adapted 15 for use in the manufacture of boots and shoes.

By way of illustration the invention is herein shown as embodied in a machine of the type disclosed in United States Letters Patent No. 932,535, granted August 31, 20 1909, on an application of Louis A. Casgrain. Machines of this general type insert a plurality of previously formed headed fastenings successively in a shoe, such machines being known commercially as loose 25 nailing machines.

In the use of machines of the type disclosed in said Letters Patent, difficulty has frequently been experienced due to failure 30 to deliver fastenings into position to be inserted in the work. This difficulty is largely increased by reason of the fact that, as is characteristic of machines of this type, the head of the machine oscillates to feed the 35 work and carries with it the raceway down which the fastenings pass to the separating mechanism for delivery from the raceway to the fastening inserting mechanism, with the result that frequently, upon movement of the 40 machine head in one direction, the fastenings in the raceway, and especially the fastenings nearest to the delivery end of the raceway, are thrown back up the raceway and away from its delivery end so that upon the 45 next operating movement of the separator slide there will be no fastening in position to be engaged by the separator and delivered to the fastening inserting mechanism.

One of the particular objects of the present invention is to remedy this defect in 50 machines of this type without sacrificing any of the well-known advantages of such

machines as heretofore constructed by providing means which will insure reliable and unfailing delivery of fastenings from the 55 raceway to the fastening inserting mechanism.

In accordance with this object of the invention, novel means is provided for preventing any retrograde or return movement 60 of the endmost fastening or fastenings in the line of fastenings in the raceway while offering no obstacle to successive orderly progression of the fastenings down the raceway to the point of separation from 65 the line of fastenings in the raceway and delivery to the fastening inserting mechanism.

In the illustrated embodiment of the invention this object is attained by a novel 70 gate or latch associated with the raceway, which device, while readily permitting passage of the successive fastenings down the raceway, operates positively by engagement successively with the respective fastenings 75 to prevent reverse or retrograde movement of the endmost fastening or fastenings up the raceway.

These and other objects and features of the invention will be apparent from the following detailed description read in connection with the appended drawings, and the novel features of the invention are set forth 80 in the appended claims.

Reference may be had to the said United 85 States Letters Patent No. 932,535 for a detailed description and explanation of various features of the illustrated machine not set forth fully herein since, except as hereinafter described and explained in detail, 90 the machine may conveniently be constructed and operated like the machine disclosed in said Letters Patent.

Although the illustrated machine is particularly designed and adapted for inserting protective fastenings of the kind known as hobnails or Hungarian nails, and the present invention relates especially to machines for inserting fastenings of these types, it is to be understood that the invention is not 100 limited in its applicability either to machines of the type set forth in said Letters Patent or to use in connection with the insertion of fastenings of the kind specified, since it is

recognized that the invention may have other and different uses and be applicable to other types of machines.

Referring to the drawings,

5 Figure 1 is a front view of the upper part of a loose nailing machine incorporating a preferred embodiment of the present invention; and

10 Fig. 2 is a side view of the lower part of the nail delivering mechanism and associated parts.

15 As is usual in machines of the type herebefore referred to, the illustrated machine, like the machine of said Letters Patent, comprises a raceway adapted to receive previously formed headed nails from a hopper, a separator for separating the endmost nail from the line of nails in the raceway and movable to present the nails successively to 20 a nail throat in position for the operation of a nail driver, and an awl having reciprocating movement to penetrate the shoe for forming successively nail receiving openings in the shoe and laterally movable to 25 feed the shoe between successive nail inserting operations of the driver. The awl, separator, nail throat, and nail driver and the raceway as well are carried by a swinging head which is operated to effect lateral work 30 feeding movement of the awl after the awl has been moved downwardly to pierce the shoe. The awl is then raised out of the work and the swinging head is swung reversely to carry the nail throat and nail driver into 35 positions over the nail receiving hole just made by the awl, after which the nail driver is operated to drive a nail into the said previously formed hole, the shoe during the nail driving operation being pressed against 40 a work plate secured to the machine frame and, in use upon some classes of work mounted on a shoe support between which and the work plate the work is clamped.

45 Referring to the drawings, the illustrated machine has a supporting frame comprising a base, a standard or column 2 and a head 14. In the head 14, as hereinbefore stated, are mounted the various parts of the fastening inserting, awl, and separator mechanisms, including a driver 104, an awl 18, a separator 86, and their supporting and operating parts, together with a nail hopper 106 and a raceway 84 formed to receive previously formed headed fastenings and inclined for passage of the fastenings down the raceway by gravity.

50 As in the machine of said Letters Patent, the machine head 14 is mounted to swing or rock about the usual pivot projection received in the machine frame, the head 14 being oscillated about its pivot by operative connections therefrom to a cam groove in a cam 50, which cam groove receives a roller carried by an arm 52 fast on a rock shaft 54, the rock shaft at its front end having de-

pending therefrom a feed arm 56 operatively connected to the head 14.

55 The driver 104 depends from a driver bar 4 mounted in a guideway in the swinging head 14. For reciprocating the driver bar 4, the upper end of the driver bar is connected by a ball joint to a link 6, in turn connected to a lever 8 operated by a spring 9, when permitted, to force the driver bar 4 downwardly, the driver bar being elevated against the tension of the driver spring 9 by a driver cam indicated at 21, carried on the front end of the main driving shaft 23 and operated in the rotation of said shaft to engage a block 27 projecting from the driver bar 4. The 60 driving shaft 23 is driven from a loose pulley which may be clutched to the shaft at the will of the operator by suitable clutch mechanism.

65 The awl 18 depends from an awl bar 16 carried in the head 14 and mounted for reciprocation therewith. For reciprocating the awl bar 16 to cause the awl 18 to penetrate the work and subsequently, after work feeding movement, to be withdrawn from 70 the work, the awl bar 16 is provided with teeth 31 arranged to engage the teeth of a toothed segment 123 carried at the outer end of a rock shaft 35, swinging movement being imparted to the head 14 to effect the 75 lateral shoe feeding movement of the awl 18 through the cam operated rock shaft and connections above described.

80 In the use of the machine, the fastenings or nails 82 pass successively from the hopper into and down the raceway 84 from which they are taken one by one by the separator 86 which is operated to cause its blade end to be inserted between the endmost nail in the line of nails in the raceway and the 85 adjacent nail and then to move said endmost nail to present it to the nail throat for the operation of the driver 104, all as fully set forth and described in detail in said Letters Patent.

86 In accordance with the present invention, a raceway cover 70, which is otherwise of usual construction, has loosely pivoted at 90 to a projection 74 from the raceway cover a gate member comprising a latch or pawl 76, pivoted at its end remote from the fastening delivery end of the raceway. A slot 78, indicated by dotted lines, is cut through the raceway cover 70 obliquely from top to bottom to receive the downwardly depending and operative end 80 of the gate member 76, the free end 80 of the gate member 76 projecting from the raceway cover 70 into the path of movement of the fastenings sufficiently so that in its normal and lowermost position it will successively engage the heads of the fastenings in the lower part of the raceway, as shown in Fig. 2, in position positively to prevent any retrograde or return movement of the fastening or fasten- 95

ings which have passed below it, thereby effectually preventing any fastenings that have passed down to the lower end of the raceway beyond the pivoted gate member or latch 76 from returning past the end thereof irrespective of the oscillation and consequent jarring of the raceway upon oscillation of the machine head 14 and irrespective of any other jarring of the raceway and the nails therein. Conveniently, in the illustrative machine, the gate member is positioned intermediate between the ends of the raceway and at a distance from the lower end thereof corresponding to the combined diameters of seven (for example) fastening heads. This distance is found fairly accurately by taking the combined diameters of that number of fastening heads as they average up in the line passing down the raceway. As the heads of the hob nails vary greatly in size, it was found to be a matter of great difficulty to position the gate member so that it would engage only the endmost fastening in the raceway to retain the same from movement up the raceway. However, the endmost fastening can be retained in position for the action of the separating mechanism by arranging the gate member so that it will engage the head of a fastening which follows the endmost fastening down the raceway. Although the gate member has been shown herein as engaging the seventh nail, it is manifest that it may be so positioned as to engage the nails nearer to or farther from the delivery end of the raceway as may be made desirable by the character of the nail heads. For example, if the heads of the nails are substantially uniform in shape and size, it might be advantageous to locate the gate member more closely adjacent to the end of the raceway.

Preferably and as shown, the gate member 76, which, as above stated, is loosely pivoted to the raceway cover and the free end 80 of which is held down in contact with the successive nails merely by gravity, is of sufficiently light construction so that, when the machine is in operation, the operative end 80 of the gate member 76 which projects into the path of progressive movement of the heads of the nails 82 as they slide down the raceway 84, does not materially retard or affect their passage to the delivery end of the raceway, the weight and momentum of the fastenings as they slide down the raceway being sufficient to counteract the weight of the operative end of the gate member so that the fastenings successively lift the end of the gate member by wedging engagement therewith, the member riding over the heads of the nails and the nails having substantially free passage beneath in sliding contact with the gate member. To facilitate the passage of the nails 82 successively down the raceway by the opera-

tive end 80 of the gate member 76, said member is pivoted so that the greater part of the weight thereof is carried by the pivot thus rendering it easy for the fastenings to displace the lower end of the member to pass below the same on their way down the raceway. However, the construction and arrangement of the member is such that its lower end remains in contact with the fastenings in the raceway, or in the absence of fastenings, with the raceway itself, and does not swing away therefrom in the oscillation of the machine head.

To prevent return movement of the fastenings up the raceway toward the hopper 80 and away from the separator, the side of the operative end 80 of the gate member 76 is shaped at 80^a to engage successively the upper sides of the heads of the nails 82 in such a manner as to insure that, whatever the agitation of the fastenings in the raceway, the operative end 80 of the gate member 76 will not be elevated or displaced by the fastenings which have passed below the gate member.

When the machine is in operation, the nails 82 successively slide down the inclined raceway 84 under and beyond the operative end 80 of the gate member 76 to the lower and delivery end of the raceway. By reason of the above described construction and arrangement of the gate member 76, the nail or nails below the operative end 80 of the gate member 76 are positively held thereby against backward movement up the raceway by engagement of the part 80^a of the gate member 76 with the heads of the successive nails as indicated in Fig. 2, the member 76 being automatically self-positioning after each nail has passed below it. As each nail reaches the delivery end of the raceway 84, it is separated from the line of fastenings by the separator 86 and carried beneath the driver 104 for insertion in the work.

The above described construction and arrangement provide reliable means for insuring that the progression of the successive fastenings to the point of operation of the separator 86 and consequently to the point of operation of the driver 104 will be regular and uninterrupted so that a fastening will always be positioned for the operation of the separator 86 at each operative movement of the separator, thus insuring regular and uninterrupted delivery of fastenings to the fastening inserting mechanism.

Having fully described my invention, what I claim as new and desire to secure by United States Letters Patent is:—

1. In a fastening inserting machine, a swinging head, mechanism carried by said swinging head for inserting previously formed fastenings successively, a raceway movable with said head for supplying fas-

90

100

110

115

120

- tenings to the fastening inserting mechanism, and a freely pivoted gate member associated with the raceway and constructed and arranged with relation to the raceway 5 to retain a plurality of fastenings below the gate member from movement away from the fastening inserting mechanism upon agitation of said fastenings by movement of the swinging head in one direction.
- 10 2. In a fastening inserting machine, fastening delivering mechanism comprising a raceway for successively supplying previously formed fastenings, separating mechanism for taking the fastenings successively 15 from the raceway and delivering them to the point of fastening insertion, and a movable gate member spaced such a distance up the raceway from the delivery end thereof that a plurality of fastenings may rest on said delivery end below the gate member and constructed and arranged with relation to the raceway to permit uninterrupted progression of the fastenings down the raceway by gravity while preventing return 20 movement up the raceway of any fastening which has progressed below said gate member.
- 15 3. In a fastening inserting machine, fastening delivering mechanism comprising a raceway for successively supplying previously formed fastenings, and a movable gate member arranged to retain a plurality of fastenings adjacent the delivery end of the raceway from return movement up the raceway and freely pivoted for displacement by the weight of the successive fastenings as they progress down the raceway to permit movement of the fastenings to the delivery end of the raceway, said pivoted 25 gate member being constructed and arranged to be automatically self-positioning after displacement by any fastening to prevent return movement of that fastening up the raceway.
- 30 4. In a fastening inserting machine, fastening delivering mechanism comprising a raceway constructed and arranged to receive previously formed headed fastenings and inclined to provide for progression of the successive fastenings down the raceway by gravity, and a gate member arranged to retain a plurality of fastenings adjacent the delivery end of said raceway from return movement up the raceway, said gate member being freely pivoted and having its operative end normally held by gravity in the path of movement of the fastenings as they pass successively down the raceway, the weight of the gate member being so proportioned to the force exerted by the successive fastenings as they pass down the raceway as to permit temporary displacement of the gate member away from the raceway by engagement of the head of a fastening 35 with the operative end of the gate member

to provide for uninterrupted progression of the fastenings down the raceway while preventing return movement up the raceway of any fastening which has passed below the operative end of the gate member.

5. In a machine for inserting fastenings, fastening delivering mechanism comprising a raceway constructed and arranged to receive previously formed headed fastenings, a separator at the delivery end of the raceway for successively separating the end-most fastening from the line of fastenings in the raceway and delivering it to the point of fastening insertion, and a movable gate member spaced from the separator for the accommodation of a plurality of fastenings therebetween and constructed and arranged to prevent accidental return movement from the delivery end of the raceway of any fastenings beyond said gate member by engagement with the heads of the successive fastenings.

6. In a fastening inserting machine, fastening delivering mechanism comprising a raceway constructed and arranged to receive and deliver previously formed fastenings, a cover for said raceway, and a movable gate member for retaining a plurality of nails at the delivery end of the raceway and comprising a member freely pivoted at one end to said raceway cover and having a depending operative end, said raceway cover being obliquely slotted for the reception of said operative end of the member and said operative end of the member projecting through the slot in the raceway cover into the path of movement of the fastenings in the raceway to prevent return movement up the raceway of any fastening below the operative end of the gate member.

7. In a machine for inserting fastenings, fastening delivering mechanism comprising an oscillating raceway constructed and arranged to receive and deliver previously formed headed fastenings, and a movable gate member associated with said raceway and freely pivoted thereto, said gate member having its operative end projecting into the path of movement of the line of fastenings in the raceway and constructed and arranged to interpose resistance to the backward movement of the fastenings sufficient to prevent return movement up the raceway of any fastening below the gate member during backward movement of the raceway and to offer a less resistance to the forward movement of the fastenings so as to permit the fastenings to pass by it readily in their movement down the raceway.

8. In a fastening driving machine, a reciprocatory fastening driving head, a raceway carried by said head for guiding fastenings forward to the driving point, a separator arranged to operate at one end of the raceway to separate a plurality of fastenings in

succession from the line of fastenings in the raceway, and means for retaining adjacent said end of the raceway and against rearward displacement longitudinally of the 5 raceway a plurality of fastenings for the separative action of the separator.

9. In a fastening driving machine, a reciprocatory fastening driving head, a raceway and raceway cover carried by said head, 10 a separator arranged to operate at the delivery end of the raceway to separate a plurality of fastenings in succession from the line of fastenings in the raceway, and means intermediate between the ends of the raceway 15 for retaining a plurality of fastenings adjacent said end of the raceway for the separative action of the separator, said means being constructed and arranged to be operated by the fastenings to pass the same toward the 20 delivery end of the raceway.

10. In a machine of the class described, fastening delivering mechanism comprising a raceway constructed and arranged to receive and deliver previously formed headed 25 fastenings, and a freely movable gate member disposed for engagement with the rear portion of the head of a fastening in the raceway back of the endmost fastening and constructed and arranged to prevent return 30 movement up the raceway of the fastenings below said member.

11. In a fastening driving machine, a re-

ciprocatory head, an inclined raceway carried by the head down which fastenings pass by gravity, a separator for removing the fastenings from the line of fastenings in the raceway, and a freely movable gate normally in engagement with the fastenings, said gate being disposed in a substantially vertical plane and having its operative end constructed and arranged to permit the fastenings to pass by it readily in their movement down the raceway but to interpose a positive stop to reverse movement of the fastenings. 35

12. In a fastening driving machine, a reciprocatory head, an inclined raceway carried by the head down which fastenings pass by gravity, a separator arranged to operate at one end of the raceway to separate fastenings in succession from the line of fastenings in the raceway, and fastening retaining means normally in engagement with the fastenings and constructed and arranged to permit the fastenings to pass it readily in their 55 passage down the raceway but to interpose a positive stop to the passage of the fastenings in the reverse direction thereby to prevent retrograde movement of the fastenings up the raceway. 60

In testimony whereof I have signed my name to this specification.

ALBERT AMOS ASTON.
